UNITED STATES PATENT OFFICE

96,059

DESIGN FOR A TEXTILE FABRIC OR SIMILAR ARTICLE OF MANUFACTURE

Albert Schumacher, Passaic, N. J., assignor to
Botany Worsted Mills, Passaic, N. J., a corpora-
tion of New Jersey

Application February 6, 1935, Serial No. 55,275

Term of patent 14 years

To all whom it may concern:

Be it known that I, Albert Schumacher, a citizen of the United States of America, residing at No. 40 Reid Avenue, in the city of Passaic, State of New Jersey, have invented a new, original, and ornamental Design for a Textile Fabric or Similar Article of Manufacture, of which the following is a specification, reference being had to the accompanying drawing, forming a part thereof, in which Fig. 1 shows a face view of a piece of textile fabric embodying my design, while Fig. 2 is a cross section along lines 2—2 of Fig. 1.

The characteristic features of the design reside in series of parallel zig-zag bands or stripes of substantially equal width extending in sub-

stantially straight direction over the entire surface of the fabric at equal distances from one another, said stripes being separated from one another by other parallel zig-zag bands or stripes cut into the nap of the fabric, said first stripes arranged in raised position with respect to said cut stripes, the individual elements of one of said raised zig-zag stripes being arranged at substantially the same level as the corresponding elements of the adjacent raised stripes.

I claim:

The ornamental design for a textile fabric or similar article of manufacture substantially as shown and described.

ALBERT SCHUMACHER.
